UNITED STATES PATENT OFFICE.

MADISON F. BATES, OF LANSING, MICHIGAN, ASSIGNOR TO BATES & EDMONDS MOTOR CO., OF LANSING, MICHIGAN.

GAS AND AIR MIXER FOR GAS-ENGINES.

SPECIFICATION forming part of Letters Patent No. 770,212, dated September 13, 1904.

Application filed June 14, 1902, Serial No. 111,613. (No model.)

To all whom it may concern:

Be it known that I, MADISON F. BATES, a citizen of the United States, residing at Lansing, county of Ingham, State of Michigan, have 5 invented a certain new and useful Improvement in Gas and Air Mixers for Gas-Engines; and I declare the following to be a full, clear, and exact description of the invention, such as will enable others skilled in the art to which 10 it pertains to make and use the same, reference being had to the accompanying drawings, which form a part of this specification.

My invention relates to gas and air mixers for gas-engines; and it consists in the improvements hereinafter described, and pointed out 15 in the claims.

Referring to the accompanying drawings, Figure 1 is a longitudinal central section of a device embodying my invention. Fig. 2 is 20 an elevation of the same looking from the right of Fig. 1.

A is a casting having a cavity formed therein for forming an inclosed chamber with an exit-passage B leading therefrom and an induction-passage C. The passage B is provided with 25 internal screw-threads, so that it may be connected with the induction-port of a gas-engine.

An opening G' of sufficient area to permit of the passage of a valve F therethrough is 30 formed at the top of the casting A and is provided with internal screw-threads.

G is a screw-threaded plug adapted to close the passage G', its thread engaging in the threads of said passage.

35 D is a cylindrical lug rising from the bottom of the casting A to about the center of the cavity in said casting. A cylindrical hole is formed through the lug D, forming a passage into the cavity in the casting A. The 40 aperture through the lug D is axially in line with the opening G'.

E is the gas-supply pipe, and it communicates with the passage through the lug D. The upper end of the lug D is faced off to 45 form a valve-seat, and a valve F is fitted thereto, guided by its stem, extending into the aperture through the lug D.

The periphery of the disk of the valve F extends beyond the periphery of the lug D,

as shown in Fig. 1. The induction-passage C 50 is located below the valve F, and the exit-passage B is located above said valve.

C' is a gridiron valve by which the area of the opening of induction-passage C may be adjusted. The plug G has a downwardly-extending projection g, which ends just above the valve F. By turning the plug G the height of the end of the lug g above the valve F may be regulated. The lug g serves to limit the lift of the valve F. 60

H is a spring secured to the casting A and adapted to press against the milled periphery of the plug G, so as to prevent the accidental turning of said plug and so as to hold said plug in the position to which it is adjusted. 65

The operation of the above-described device is as follows: The casting A is connected substantially air-tight to the intake of the gas-engine, so that the charge for the engine will be drawn through said casting by way of 70 the passage B. When the engine is started, the area of the induction-passage C is considerably contracted by means of the valve C', so that the vacuum formed in the cavity of the casting A will cause the valve F to rise 75 and admit considerable gas through the pipe E, so that a rich mixture will be formed to start the engine. When the engine is in motion, the valve C' is turned to allow a larger area through the induction-passage C. Air 80 is drawn through said passage and passes across the cavity in the casting A in an inclined upward direction, pressing under the area of the disk of the valve F, which extends beyond the lug D, and raising or helping to raise the valve F to open the passage for the gas. The height to which the valve F may rise is limited by its striking against the lower end of the lug g. The gas-passage 85 may be also used as a conduit for gasoline. 90

What I claim is—

1. The combination of an inclosed chamber, a gas-passage extending thereto, a valve-seat intermediate the gas inlet and outlet passage, its upper extremity being higher than the inlet-opening, a valve-disk whose outer edge extends beyond said valve-seat and whose stem 95 engages loosely therein, and an outlet-passage

above said valve-disk, the area of the passage-space above said valve-disk being greater than that of the inlet-passage.

2. The combination of an inclosed chamber, 5 a gas-passage extending thereinto near the bottom thereof, an outlet-port on the opposite side thereof and near the top thereof, means for controlling and regulating the flow through said inlet-port, a raised valve-seat intermediate the inlet and outlet openings, the area of 10 the passage past its crowning disk being greater than the inlet-passage, a valve-disk resting on the top and extending past the outer edge thereof, and means for regulating the size of the passage past said valve-disk, substantially as described. 15

3. The combination of an inclosed chamber, a gas-passage extending thereinto near the base thereof, an outlet-passage in the opposite side thereof near its top, a raised valve-seat intermediate the two openings having an

opening central thereto and to the containing-chamber, a valve-disk resting upon the upper extremity thereof, its edges extending beyond said valve-seat, substantially as described. 25

4. In a gas and air mixer, the combination of an inclosed chamber, a gas-passage leading thereinto near its bottom, an outlet-passage leading from the opposite side thereof near its top, an intermediate raised valve-seat, a valve-disk resting on the top thereof, its edges extending past the sides thereof, means for regulating the flow of gas thereinto and means for regulating the size of the passage past said valve-disk, substantially as described. 30 35

In testimony whereof I sign this specification in the presence of two witnesses.

MADISON F. BATES.
